J. KRAUTH

APPARATUS FOR PLAYING SKITTLES

Filed Dec. 23, 1927

Inventor:
Johannes Krauth
By *Frothingham* attorney

UNITED STATES PATENT OFFICE.

JULIUS KRAUTH, OF SONTHEIM-HEILBRONN, GERMANY.

APPARATUS FOR PLAYING SKITTLES.

Application filed December 23, 1927, Serial No. 242 209, and in Germany February 1, 1927.

This invention relates to an apparatus for playing a game of skittles by means of a suspended ball.

According to the invention the vertical holding system carrying the skittles is suspended so that it can be oscillated in a direction perpendicular to the pendulum movement of the ball.

An embodiment of the invention is illustrated, by way of example, in the accompanying drawing, in which

Fig. 1 shows the apparatus in front elevation.

Fig. 2 is a side-elevation, partly in cross-section.

Fig. 3 shows in elevation the clockwork.

Fig. 4 is a top plan view of Fig. 3.

Figs. 5 and 6 illustrate suspending devices for the ball when this ball is designed to strike the skittles only at its backward oscillation.

The apparatus is mounted on a base plate *a* in which a frame-shaped vertical support *b* is rotatably mounted by means of a pivot-pin *c* so that this support can be rotated or adjusted to be brought to in front of each player of a number of players sitting around a table.

In the upper end of the vertical support *b* a horizontal-arm *d* is fixed, to the free end of which a pendulum *e* carrying a ball *f* is hingedly connected.

In the upper surface of arm *d* cavities *g* are provided with which engage pointed screws *h* which carry the system on which the skittles *i* are mounted and which is constructed like a swing. As this system is supported only at two points the supporting surface or friction surface is as small as possible.

The pointed screws *h* are screwed through a rocking beam *k* from which laterally inclined arms *m* extend downward to the lower ends of which a holder *l* of curved cross section is fixed. The skittles *i* are hingedly mounted on the holder *l* so that a skittle which has been struck by the ball falls over into a downwardly inclined position.

Instead of skittles any other figures might be used and mounted on the holder *l*.

In the construction shown the ball is moved perpendicular to the direction in which the swing or skittle-holder moves.

The swing-system *k*, *l*, *m* is operated by a clockwork *n* of the kind used in pendulum clocks, in order to ensure a uniform movement of the skittles. The swing is connected

with the clockwork by means of a pin *o* fixed in the rocking beam *k* and engaging with a slot in the pallets *p*. The pendulum movement is transmitted upon the swing by the pallets *k* engaging with the balance-wheel. For regulating the number of oscillations of the swing, a counter-weight *s* is arranged on the rocking beam *k*.

In the apparatus shown by way of example the skittles *i* can be struck by the ball *f*, while the swing is oscillating to and fro. The apparatus might however be arranged so that the skittles *i* are struck by the ball *f* only when this ball is swinging backward the ball moving at the forward oscillation above the heads of the skittles.

In this form of construction the struck skittles drop only towards the players.

With this object in view the ball is suspended as shown in Figs. 5 and 6. On the horizontal arm *d* a vertical element *u* carrying the ball *f* and having a vertical slot *t* is loosely mounted. The element *u* and with the same the ball *f* are held in the position of rest by a bolt *v* engaging with a curved extension at the lower end of slot *t* (Fig. 5). The element *u* might be held in the position of rest by means of a latch *x* (Fig. 6) bearing on the pin *v* which engages with the lower end of a straight slot *t*.

When the ball is being pushed, the element *u* will strike against an abutment-pin *y* and is then raised so that the pin *v* gets out of the curved extension *w* of slot *t*, or the pivotally mounted latch *x* oscillates and liberates the bolt *v*. The element *u* will then drop on the pin *v* of the length of slot *t* so that the ball *f*, which in the position of rest was standing a certain distance above the heads of the skittles, can strike against a skittle at the backward oscillation.

I claim:—

1. An apparatus for playing at skittles, comprising in combination with a base plate, a vertical frame-shaped support rotatably mounted on said base plate, a horizontal arm fixed in said support, a ball suspended pendulum-like in the front end of said horizontal arm, and a swing-like holder for the skittles oscillating perpendicularly to the swinging movement of said ball.

2. An apparatus as specified in claim 1, comprising a clockwork for mechanically oscillating said swing-like skittle holder.

3. An apparatus as specified in claim 1, comprising in combination with a horizontal

arm and a swing-like skittle holder, pointed screws supporting said skittle holder system on said horizontal arm.

4. An apparatus as specified in claim 1, comprising in combination with the swing-like skittle holder system, a counter-weight for regulating the oscillations of said holder system.

5. An apparatus as specified in claim 1, comprising in combination with the swing-like holder system, skittles hingedly mounted on said holder so that the skittles struck by the ball drop forward.

6. An apparatus as specified in claim 1, comprising in combination with the swing-like holder system, skittles hingedly mounted on said holder so that the skittles struck by the ball drop backward.

7. In an apparatus as specified in claim 1, the pendulum-like ball, and means for locking said pendulum-ball in the position of rest at a certain distance above the heads of the skittle, to make the same automatically drop when the ball is being swung.

8. In an apparatus as specified in claim 1, in combination with the support and the horizontal arm in said support, a pendulum-ball, an element movably mounted on the front end of said horizontal arm and having a vertical slot curved inward and upward at the lower end, a pin fixed in said horizontal arm engaging with said slot, a vertical rod fixed on the lower end of said element, and a ball fixed on the lower end of said rod so that when said ball is in the position of rest said curved lower end of said slot of said element engages over said pin so that the element and through the same said ball is held in raised position and is automatically lowered when it is swung back as said element slips on said pin.

9. An apparatus as specified in claim 1, comprising in combination with the base plate, a pivot pin in said base plate, and a vertical frame like support adapted to rotate around said pivot pin.

In testimony whereof I affix my signature.
JULIUS KRAUTH.
